UNITED STATES PATENT OFFICE.

CHARLES PATTON HENRY, OF FAIRFAX, VIRGINIA.

TIME SLOT METER.

Application filed August 16, 1921. Serial No. 492,811.

To all whom it may concern:

Be it known that I, CHARLES P. HENRY, a citizen of the United States, residing at Fairfax, in the county of Fairfax and State 5 of Virginia, have invented certain new and useful Improvements in Time Slot Meters, of which the following is a specification, reference being had therein to the accompanying drawings.

10 This invention relates to a time slot meter, and the object of the invention is the construction of a meter which will receive a coin, and upon the receipt of the coin, the meter can be manually operated to turn on 15 the source of supply for lights, and permit the lights to burn for a predetermined length of time; upon the expiration of the time period, the machine will operate for closing the source of supply, whereby the 20 lights will go out or be extinguished.

With this and other objects in view, my invention comprises certain novel combinations, constructions and arrangements of parts as will be hereinafter described, illustrated in the accompanying drawings, and more particularly pointed out in the appended claims.

In the drawings:

Figure 1 is a view of my meter, taken on line 1—1, Fig. 2, and looking in the direction of the arrows.

Figure 2 is a sectional view, taken on line 2—2, Fig. 1, and looking in the direction of the arrows pointing toward the numerals 2.

35 Figure 3 is a sectional view, taken on line 3—3, Fig. 1, and looking in the direction of the arrows pointing toward the numerals 3.

Figure 4 is a plan view of the clock-dial 40 and the hand-operated device assembled therewith, taken on line 4—4, Fig. 3.

Figure 5 is an enlarged plan view of the start and stop device for the clock.

Figure 6 is an enlarged, sectional view, 45 taken on line 6—6, Fig. 3.

Referring to the drawings by numerals, 1 designates the casing, and 2 is the hinged door mounted thereon. A manually-operated shaft 3 extends across the casing 1, and is provided with a handle 4, Fig. 1, which allows the shaft to be rotated by a person. A collar 5 is secured to the shaft 3, and in this collar is formed a coin-receiving pocket 6. A coin slot 7 has its lower end positioned contiguous to the collar 5, so that a coin 8 will be placed in the pocket

6 and retained in said pocket as the shaft 3 is rotated (see Fig. 2), permitting the coin 8 to engage the lower hooked end 9 of the catch-link 10. The catch-link 10 is 60 pivotally mounted, at 11, upon the angle-link 12; link 12 is pivotally mounted, at 13, upon the side of the casing 1. A hook 14 is formed upon the outer end of link 12 and this hook is hooked in the lower end of sectional, adjustable rod 15. The upper end of rod 15 is pivotally connected to the outer end of lever 16. Lever 16 is pivotally mounted on valve 17 of the gas supply pipe 18. A gas cut-off valve 19 is placed on the pipe 18, so that if my meter is not being used for turning on and off the gas supply, the gas can be cut off by valve 19, and the opening and closing of the valve at 17 will be 70 of no consequence.

A fixed contact 20 is fastened to the side of the casing and a contact 21 is formed upon the outer end of arm 22, which arm 22 is pivotally mounted, at 23, upon the side of the casing. A short spring 24 is fastened, at its upper end, to pulley 25, which pulley is carried by bracket 26; the lower end of spring 24 is fastened to arm 22, and the upper end of long spring 27 is also fastened to arm 22. The lower end of spring 27 is fastened to cable 28, which cable passes around pulley 29 and is connected to lever 16. A rod 30 is supported upon bracket 31, and the cable 28 passes over the top of rod 30, so that when the lever 16 is in the 90 dotted position, shown in Fig. 1, which is the set ("on") position, cable 28 will be drawn across rod 30, resulting in pulling down on the arm 22, causing contacts 20 and 21 to engage, closing the circuit through wires 32 and 33, permitting the lights to burn in the room, or building.

95 A suitable bumper or stop device 34 is attached to the shelf 35^a against which the lever 16 may bear or "hit" when it moves to its unset or "off" position. A cut-off switch 35 is attached to the wire 32, so that the lights may be cut-off by the operator, if he so desires.

100 A coil spring 36 is fastened at its lower end to the bottom of the casing and its upper end is fastened, at 37, to lever 16, so that the tendency of the spring is to hold the lever in an unset position, as shown in full lines in Fig. 1. On the inner end of the 110 lever 16 is an angle catch plate 30^a which catch plate 30^a is adapted to move into en-

gagement with the socket portion 39 of the pivotally-supported latch plate 40. When the catch is in the hooked position, shown in dotted lines in Fig. 1, the contacts 20 and 5 21 will be in engagement and the lights in the room or building will be burning.

The clock mechanism 41 is supported upon the platform 42, and the clock mechanism is provided with an insulating dial 43. This clock mechanism is provided with the usual minute and hour hands. A bracket 44 is arranged above the dial, and slidably mounted in bracket 44 is a clock-hand operated device 45; this device 45 includes angle 10 rod 46, on the lower end of which is sleeve 47, Fig. 6. Trigger fingers 48 are adjustably mounted in sleeve 47, and these fingers are adapted to engage at their lower, outer ends the insulating dial 43. The outer end of 15 angle rod 46 is adapted to engage the inclined rod 49. The minute hand, Fig. 4, engages one of the fingers 48, rotating the device 45 as the hand moves over the dial, causing the outer end of rod 46 to engage 20 inclined rod 49, whereupon, a circuit will be closed through the source of supply 50, Fig. 1, wire 51, clock mechanism and hands, device 45, rod 49, wire 52 and solenoid 53. This closing of the circuit energizes solenoid 25 53, resulting in the repelling of the solenoid core 53' and the latch plate 40, whereupon, the catch plate 30^a will be released, permitting spring 36 to draw the lever 16 to its 30 unset position, shown in full lines in Fig. 35 1, thereby allowing spring 24 to pull upon the contact 21, braking the light circuit. The rod 49 is inclined so that when the clock-hand operated device is permitted to drop from the full line position, shown in 40 Fig. 1 to the dotted position, on the dial, it will not drop in its old place but in a new place, whereby the device 45 must be again rotated to cause the solenoid 53 to be energized, releasing the lever, to permit the 45 lever to return to its unset or normal position by the action of spring 36.

I have provided a start and stop device 54 for the clock mechanism 41, which device comprises a base 55 carried by bracket 56, Fig. 3. A start and stop wheel 57 of the clock mechanism 41 is supported so as to partly overhang the base 55. A sliding brake member 58 rests on the base 55, and this brake member is provided with a cut-out portion 59, which is adapted to be positioned over part of wheel 57. A soft covering or piece of fabric 60 is fastened over part of the brake member 58, to engage the cogs or wheel 57 to stop the rotary movement of the wheel. When the inner end of the lever 16 moves upwardly to the position shown by dotted lines in Fig. 1, such movement will allow cable 61 to travel inwardly under pulley 62, Fig. 5, which will 65 permit the coil spring 63 to draw brake

member 58 inwardly, so as to place the cut-out portion 59 over wheel 57, permitting the clock mechanism to operate for swinging or moving the hands over the dial 43. Upon the solenoid 53 being energized and 70 the inner end of the lever moving down to the position shown by full lines in Fig. 1, cable 61 will be drawn upon, whereas, cable 64 will be slightly loosened to permit the spring catch 65 to enter the notch 66 and hold the brake member against the wheel 57, as shown in Fig. 5, stopping the clock mechanism from operating the hands.

A cam 67 is fastened to shaft 3 and this cam is provided with a flat portion 68 which 80 is engaged by a hinged plate or bar 69. A hinged plate 70 is mounted upon an insulating block 71, which block 71 is carried upon standard 72. A spring 73 is connected to bar 69 and standard 72. The outer end of plate 70 is connected by cable 74 to spring 36. A contact 75 is attached to plate 70 and a contact 76 is fastened to the insulating block 71. Wire 32 is connected to contact 75 and wire 33 is connected to contact 76, so that when the operator rotates shaft 3, causing the round edge of cam 67 to lift the bar 69, the circuit will be broken at the contacts 75 and 76, and will not be closed until the flat portion 68 is again 95 engaged by the bar 69. By this construction the circuit may be broken merely by turning shaft 3, without necessitating entering the casing for operating the switch 35.

Backward movement of shaft 3 is prevented by the usual dog and cog device 77.

The coin-receiving box or receptacle 78 is placed under sleeve 5 for receiving the coins 8 as they drop from the pocket 6. A magnet 79, Fig. 1, is provided for drawing slugs or 105 fraudulent coins through slot 80, Fig. 1, of the chute 7^a.

The operation of the meter is as follows: A coin is placed in slot 7 of chute 7^a and passes into pocket 6 of collar 5. Then the operator grasps handle 5 and rotates shaft 3, causing the coin to engage catching link 10 drawing the outer end of the lever 16 to the position shown by dotted lines in Fig. 1, whereupon the catch plate hooks into the latch plate 40, permitting the cable 81, passing over pulley 82, to lower the clock-hand operated device 45 upon the dial 43, and at the same time cable 64 will cause spring catch 65 to release the sliding brake member 58 so that the cut-out portion 59 will be over the wheel 57 instantaneously permitting the clock mechanism to operate for causing the hand to rotate device 45, for instance, for fifteen minutes (if that time is the amount originally determined upon), allowing the lights to burn for fifteen minutes, for, say, ten cents, whereupon, the angle rod, striking the inclined rod 49, will result in the solenoid 53 being energized, 130

instantaneously resulting in the latch plate 40 being repelled, dislodging the catch plate 30, allowing spring 36 to pull the inner end of the lever downwardly, braking the lamp circuit at contacts 20 and 21, or in the case of gas being used, closing or cutting off the supply of gas in pipe 18 at valve 17.

I have found from actual experience with my meter that it works in an efficient and 10 satisfactory manner, and by the use of my meter, an attendant is not required in pool and billiard rooms where lights are required for playing the game, as the users of the room will have to place a coin or money in 15 the meter for continuing the supply of light while playing.

While I have described the preferred embodiment of my invention, and have illustrated the same in the accompanying drawings, certain minor changes or alterations 20 may appear to one skilled in the art to which this invention relates, during the extensive manufacture of the same and I, therefore, reserve the right to make such alterations or 25 changes as shall fairly fall within the scope of the appended claims.

What I claim is:

1. In a device of the class described, the 30 combination of a support having a valve provided with a lever, means for manually

shifting said lever in one direction, a catch plate on said lever, a latch plate pivotally carried by said support for engaging said catch plate for holding said lever in a set position, a solenoid engaging said latch 35 plate, a fixedly supported inclined rod, a pivotally supported angle rod carried near said inclined rod, means electrically connecting said rods to said solenoid, and means for turning said angle rod to engage said inclined rod, as and for the purposes set forth. 40

2. In a device of the class described, the combination of a support having a valve provided with a lever, means for manually shifting said lever in one direction, a catch 45 plate on said lever, a latch plate pivotally carried by said support for engaging said catch plate for holding said lever in a set position, a solenoid engaging said latch plate, a fixedly supported inclined rod, a 50 pivotally supported angle rod carried near said inclined rod, said angle rod having fingers on its lower end, a cable connected to said lever and to said angle rod, and a clock mechanism below said fingers, as and for the 55 purposes set forth.

In testimony whereof I hereunto affix my signature.

CHARLES PATTON HENRY.
